UNITED STATES PATENT OFFICE

DAVID D. LEVITT, OF ROCHESTER, NEW YORK

GAME APPARATUS

Application filed June 1, 1931. Serial No. 541,269.

My present invention relates to games and toys and it has for its object to provide an improved game apparatus of the type in which projectiles are fired at one or more targets through the use of a catapult or similar device. The improvements are directed in part toward means for resetting the target; means for collecting the projectiles; means for reloading the catapult or projecting device; and toward means for placing these instrumentalities under the control of a check or coin mechanism whereby the player pays in this way for the privilege of playing the game. A further object of the invention is to provide a new and improved catapult for firing the projectiles.

To these and other ends, the invention resides in certain improvements and combinations of parts, all as will be hereinafter more fully described, the novel features being pointed out in the claims at the end of the specification.

In the drawings:

Fig. 1 is a front elevation of a game apparatus constructed in accordance with and illustrating one embodiment of my invention;

Fig. 2 is a side view thereof;

Fig. 3 is an enlarged central vertical section therethrough;

Fig. 4 is an enlarged detailed elevation, partly in section, of one of the projectile collecting mediums;

Fig. 5 is a front view similar to Fig. 1, but with the front cover plate removed;

Fig. 6 is an enlarged elevation, partly in section, of a fragment of a wall of the cabinet showing the check controlled mechanism in detail;

Fig. 7 is a bottom view of the catapult mounting;

Fig. 8 is an enlarged vertical section, partly broken away, taken centrally through the catapult device and showing the same loaded;

Fig. 9 is a fragmentary side view of the catapult mechanism;

Fig. 10 is a section through the catapult taken on the line 10—10 of Fig. 8;

Fig. 11 is an elevation of the catapult

mechanism similar to Fig. 9 but viewed from the opposite side, and

Fig. 12 is a top view, showing the loading slide in detail.

Similar reference numerals throughout the several views indicate the same parts.

In the illustrated embodiment of the invention there is provided a cabinet comprising a base or body member 1 having a rear wall 2 rising from the rear edge thereof and provided with a door 3. The cabinet also has two side walls 4 connected by a short top wall 5. The front wall 6 inclines upwardly and rearwardly from the bottom wall and is provided with a transparent window 7 near its upper portion.

Arranged within the cabinet is a cross bar 8 on which are pivoted at 9 a number of targets 10. Each of these targets, in this instance, simulates a man and lies so as to be visible through the transparent glass or window 7.

Adjacent to the base of the cabinet is arranged a projecting mechanism for a projectile such as small spheres 11. This projecting mechanism or catapult embodies a carriage 12 mounted to swing about an upright axis 13 and having its movement limited in two directions by stops 14. This carriage has projecting upwardly and rearwardly therefrom a barrel 15 with a projectile receiving chamber 16 at its front and lower end, said chamber being open at 17 so that a projecting device may enter the chamber, engage a projectile 11 therein and impel it through the tube upwardly and rearwardly toward one of the targets in order to displace said target rearwardly, and downwardly when hit as shown in dotted lines in Fig. 3. The direction the projectile takes is determined by the position of the projecting apparatus which is positioned through a handle 18 extending forwardly through an opening 19 in the front wall of the cabinet.

The user of the machine is required to make a guess as to the direction in which the barrel 15 is pointed as the barrel is hidden behind the front wall, and by practice the user can direct the barrel toward any one of the targets after becoming familiar with the "feel" 100

of the adjustments. As the targets are spaced apart, the user, in many instances, positions the barrel so that the projectile passes between the targets. The projectile is 5 expelled through the barrel 15 by a hammer 20 pivoted at 21 to the swinging carriage and having the firing pin 22 adapted to pass through the opening 17 in the receiver and engage a projectile in the receiver. The hammer 20 is normally pressed toward projecting 10 position by a spring 23 and is withdrawn from projecting position by a trigger 24 which is pivoted at 21 on an axis in common with that of the hammer. This trigger carries 15 a latch or detent 25 which is pivoted at 26 on the trigger 24 and is normally held toward latching position by a spring 27. The free end of the hammer is curved or beveled at 28 so that the nose 29 of the latch or detent 20 25 will engage a shoulder 30 on the hammer and hold the latter toward the trigger 24. When the trigger 24 is engaged with the hammer and is then lowered, this detent 25 will engage a trip 31 and will release the hammer 20 permitting the firing pin 22 of the latter 25 to engage the projectile 11 under the influence of spring 23, and project the same upwardly and rearwardly through the barrel 15.

30 With the end in view of feeding the projectiles 11 one at a time to the receiving chamber 16, the latter is extended downwardly and rearwardly from the barrel at 32 (Fig. 8) and has arranged therein a loader in the form 35 of a slide 33 which has a pocket 34 extending therethrough, in which the projectiles are received, as in Figs. 3 and 8, and from which they are projected by the hammer 20. Communicating with the loading slide is a slightly 40 inclined tubular magazine 35 leading to the receiver chamber extension 32 from a hopper 36. When the slide is in a position to present a projectile 11 to the barrel 15, communication from the magazine tube 35 to the receiver extension 32 is closed by the slide. 45 When the slide moves downwardly and rearwardly the pocket or opening 34 is presented to the magazine 35 and the projectile 11 passes into the pocket 34 to be fed into alignment with the barrel. Movement of the loading slide 33 is effected through an arm 37 rigid with the trigger 24. This arm engages a lateral projection 38 on an arm 39 which has a bifurcated free end 40 straddling a lug or projection 41 50 extended through a slot 42 in the receiver extension 32 from the loading slide 33. A spring arm 43 also engages the projection 38 to move the arm 39 in the direction opposite to that in which it is moved by the arm 37 and it is 55 this spring, acting thus indirectly and through arm 37, that returns the trigger. When the trigger 24 is moved upwardly to pull the hammer 20 downwardly, the slide 33 moves rearwardly and downwardly to pick 60 up one of the projectiles 11 and transfer it

from the magazine to the chamber as the slide 33 is again moved upwardly and forwardly. Just before the end of the downward movement of the trigger 24 is reached, the hammer 20 is released and projects the 70 projectile through the barrel 15.

With the end in view of causing those projectiles which do not reach the target to be returned to the magazine, so that the user of the machine may have another chance for 75 such projectiles, a chamber 44 is provided between the end of the barrel 15 and the target. This chamber is visible through the window 7 and has an inclined wall 45 leading from the rail or cross bar 8 downwardly 80 and forwardly. A curved ledge 46 in the chamber on the wall 45 is provided with a longitudinally extending slot 47 beneath which is arranged a slide 48. This slide has both a longitudinal movement and a 85 loose lateral movement on the curved ledge 46 and has an opening 49 through which the barrel 15 projects, the two movements being necessary because of the fact that the barrel 15 swings on the vertical pivot 13. 90 The slide will move with the barrel and provide a closed connection between the barrel and the curved ledge 46 notwithstanding the movement or the shifting of the barrel. At the lower end of the wall 45 and at opposite 95 ends of the curved ledge 46 are two openings or discharge passages 50 which by passageways 51 discharge into the hopper 36 and thence to the magazine 35 so that projectiles which do not reach the targets may be used for other plays. Those projectiles which strike the targets or pass between them are received in a collecting trough 52 which has a tube 53 projecting downwardly and forwardly to discharge into the hopper 36. 100

105 It may be here said that the invention contemplates incorporation in the machine of a coin control, the idea being that a predetermined number of projectiles 11 shall be placed at the disposal of the player upon the deposit of a coin of a predetermined denomination in the coin controlled mechanism associated with the structure heretofore described to furnish the actuating means for the release of the projectiles accumulated 110 during a previous operation. In order to prevent the discharge of the projectiles 11 into the magazine 35, until all of the projectiles in the magazine 35 have been fired, a gate 54 is provided which enters a slot 55 115 in the tube 53 leading from collector 52 to prevent the passage of the projectiles 11 when the gate is in closing position. This gate, in this instance, is supported by an arm 56 on a rockshaft 57. This also carries a double arm member 58, one arm of said member having a spring 59 secured thereto normally to hold the gate 54 in closed position. The other arm on this member 58 extends in the path of a coin chute 60 so that 120

125 130

a coin 61, after passing down said chute, may be caused by a rotary controller 62 to engage said member 58 and shift the gate to open position, in order that a definite number of projectiles in the collector 52 and tube 53 may be deposited in the hopper 36 and thence reach the magazine 35. The controller 62 is in the form of a disk having notches 63 and rotatable with a shaft 64 which extends to the exterior of the casing and has a knob 65 through which the controller may be turned. Of course, unless a coin is deposited in the coin slot 60 and enters one of the notches or coin seats 63, the member 58 cannot be shifted. The resetting of the targets 10 may be effected by a cross piece 67 lying in back of the targets and forming part of a yoke embodying arms 66 which are also mounted on the rock shaft 57 and are swung to reset the targets at the time that the gate 54 is lifted through the coin controlled mechanism.

It is thought that the function and mode of operation may be followed from the above description, but to review it briefly, it will be assumed that when an operator approaches a machine, the projectiles 11 will be accumulated in the collector 52 and tube 53 behind the gate 54, which is in operative position, as in Fig. 3. The deposit of the coin 61 in coin slot 60 enables the rotary actuating disk 62 to cause it to lift lever 58 against spring 59, raising the gate 54 and at the same time bringing cross piece of yoke 56 forwardly to reset the targets 10, or such of them as may be down. The said projectiles 11 thus fall into hopper 36 and roll into the magazine tube 35. The catapult or projectile barrel 15 is then moved about in an arcuate path by means of the handle 18 with the operator's one hand, while, after aim is taken, the trigger 24 is depressed and released with the other hand. When the full charge of projectiles has been exhausted and collected by collector 52 or reshot from chamber 44, which also acts as a collector to that extent, the play on the coin deposited is terminated.

What I claim as my invention and desire to secure by Letters Patent is:

1. In a game apparatus, the combination with a displaceable target having hit registering and set positions, of means for firing a projectile in the direction of the target, a loading device for said means, a collector for the projectiles when fired delivering to the loading device, and check controlled means arranged to normally accumulate the projectiles in the collector for permitting their transfer to the loading device and for simultaneously resetting the target when displaced.

2. In a game apparatus, the combination with a displaceable target having hit registering and set positions, of means for firing

a projectile in the direction of the target, a loading device for said means, a collector for the projectiles when fired delivering to the loading device, check controlled means arranged to normally accumulate the projectiles in the collector and permitting their transfer to the loading device when released, and means movable with the last mentioned means for resetting the target.

3. In a game apparatus, the combination with a displaceable target having hit registering and set positions, of means for firing a projectile in the direction of the target, a loading device for said means, a collector for the projectiles when fired, a runway leading from the collector to the loading device, a gate normally blocking the runway, check controlled mechanism for releasing the gate, and means operable with the latter under the same control for resetting the target.

4. In a game apparatus, the combination with a displaceable target having hit registering and set positions, of means for firing a projectile in the direction of the target, a loading device for said means, a collector for the projectiles which are fired beyond the target delivering to the loading device, check controlled means arranged to normally accumulate such projectiles in the collector, for permitting their transfer to the loading device and for simultaneously resetting the target when displaced, and a second collector arranged to receive the projectiles that do not pass the target, said second collector being arranged to automatically deliver the projectiles to the loading device independently of the check controlled means.

5. In a game apparatus, the combination with a displaceable target, of means for firing a projectile in the direction of the target, a loading device for said means, a collector for the projectiles which are fired beyond the target delivering to the loading device, check controlled means arranged to normally accumulate such projectiles in the collector and permitting their transfer to the loading device when released, a second collector arranged to receive the projectiles that do not pass the target, said second collector being arranged to deliver the projectiles to the loading device independently of the check controlled means, and means operable with the check controlled means for resetting the target.

6. In a game apparatus, the combination with a displaceable target having hit registering and set positions, and means for firing a projectile in the direction thereof, of a loading device for the latter embodying a magazine, a collector in rear of the target adapted to deliver the fired projectiles back to the magazine, a collector in front of the target for automatically delivering fired projectiles back to the magazine, when said projectiles do not pass the target and coin con-

trolled means for accumulating projectiles in the first mentioned collector independently of the operation of the second named collector and for releasing the projectiles to the 5 firing means and for simultaneously resetting the target when displaced.

7. In a game apparatus, the combination with a plurality of independently pivoted upright targets adapted to be knocked over 10 when hit, of means for firing a projectile in the direction of the targets, a loading device for said means, a collector for the projectiles when fired delivering to the loading device and embodying a chute, a gate in the chute 15 arranged to accumulate the projectiles, a resetting bar extending in rear of the targets and adapted to reset them all at one movement, and check controlled means for concomitantly actuating the resetting bar and 20 releasing the gate.

8. In a game apparatus, the combination with a row of independently pivoted upright targets adapted to be knocked over when hit, of means for firing a projectile in the direction 25 of the targets, a loading device for said means, a collector for the projectiles when fired delivering to the loading device and embodying a chute, a rock shaft, check controlled means for rocking the shaft, a gate 30 arm on the shaft normally in position to accumulate projectiles in the chute, and an arm on the shaft for resetting the row of targets when the shaft is rocked to release the gate.

9. In a game apparatus, the combination 35 with a displaceable target having hit registering and set positions, and means for firing a projectile in the direction of the target embodying a loading device and a magazine associated therewith, of a projectile collecting 40 hopper in rear of the target, a chute leading from the hopper to the magazine, a gate arranged to accumulate projectiles in the chute, collecting means in front of the target for automatically delivering into the magazine 45 projectiles which do not pass the target, and check controlled means for releasing the gate and for simultaneously resetting the target when displaced.

10. In a game apparatus, the combination 50 with a displaceable target having hit registering and set positions, of means for firing a projectile in the direction of the target, a loading device for said means, a collector for the projectiles when fired delivering to the 55 loading device, and check controlled means for releasing the projectiles from the collector and for simultaneously resetting the target when displaced.

11. In a game apparatus, the combination 60 with a target having hit registering and set positions, of means for firing a projectile in the direction of the target, and check controlled means for resetting the latter and for simultaneously delivering projectiles to the 65 firing means.

12. In a game apparatus, the combination with a target having hit registering and set positions, of means for firing a projectile in the direction of the target, and check controlled means for resetting the latter and also 70 admitting projectiles to the firing means.

13. In a game apparatus, the combination with an elevated target, and means arranged in front thereof for collecting projectiles, of means arranged at a lower level than the target for firing projectiles in the direction of the target and having a barrel portion projecting through the collecting means. 75

14. In a game apparatus, the combination with an elevated target, and means arranged in front thereof for collecting projectiles, comprising an incline and a ledge projecting therefrom having a slide therein, of swinging means arranged at a lower level than the target for firing projectiles in the direction 80 of the latter and having a barrel portion projecting through and closely fitting the slide. 85
